UNITED STATES PATENT OFFICE.

FREDERICK E. KOHLER, OF CANTON, OHIO.

LAWN-RAKE.

SPECIFICATION forming part of Letters Patent No. 554,824, dated February 18, 1896.

Application filed November 26, 1894. Renewed January 6, 1896. Serial No. 574,559. (No model.)

To all whom it may concern:

Be it known that I, FREDERICK E. KOHLER, a citizen of the United States, and a resident of Canton, county of Stark, State of Ohio, have invented a new and useful Improvement in Lawn-Rakes, of which the following is a full, clear, and exact description, reference being had to the accompanying drawings, making part of this specification.

10 My invention relates to improvements in lawn-rakes; and it consists in certain features of construction and combination of parts, as will be hereinafter described and claimed.

Figure 1 of the accompanying drawings is a view in perspective of my invention. Fig. 2 is a cross-section through the head and one prong of the handle-socket on a line from x to x . Fig. 3 is a cross-section of the head on a line from z to z .

20 The particular feature of my invention relates to the formation of the rake-head A, as heretofore constructed, in simple U form or from "channel-iron." There has been a lack of rigidity or ability to resist torsional strain 25 when the teeth at the end portions of the head are resisted by engagement with the sward or other resistance, and to provide against twisting of the head, as before stated, I have provided a rake-head A, made or stamped from 30 suitable sheet metal, having parallel sides a a and a connecting end or bottom portion formed on transverse curves having summits b b' and valleys d d', the valleys touching a line drawn from z to z , showing that the 35 central portion of the metal has been moved bodily inside of the inner face of the side valleys d', thus forming a truss in the line to resist torsional strain on the head, as hereinbefore mentioned.

40 The sides a a are provided with series of coinciding apertures e, in which are placed U-shaped teeth B, the end portions of which are bent forward or transverse the head, as shown.

45 As a means of securing the teeth B in the head, the apertures e may be placed a distance in advance of the rear face of the curve b', and when the teeth are pressed in the front side will bind hard against the rear face b' of 50 the rake-head, in which position when the rake-head is tinned or passed through the process of tinning the teeth become firmly

soldered to the rear face of the curved portion b' of the head, as shown in Fig. 3.

The handle C is secured to the head by a 55 socket D; having bifurcated prongs E, that embrace the head. On the rear face of the prongs E and between the fingers h is provided a rearward projection k, that takes between the corrugations or curves b b in the 60 valley d against the front face of the head, as shown. Through the end portions h is passed a screw-bolt m at the rear of the sides a, by which the socket D is secured to the head.

For shipping, the socket and handle may be 65 removed, the rakes nested, and the handles bundled, thereby reducing the bulk and cost of transportation.

Having thus fully described the nature and object of my invention, what I claim is— 70

1. The combination, in a rake, of a U-shaped head, made of sheet metal, having parallel top and bottom portions, provided with a series of coinciding apertures to receive teeth, a corrugated side portion, teeth passed through said apertures and bent transverse the head, and a handle-socket adapted to embrace the head and provided with projections which take in and connect with said corrugated side, substantially as described. 80

2. The combination, in a rake, of a U-shaped head, made of sheet metal, having parallel top and bottom sides, provided with series of coinciding apertures to receive teeth, a corrugated side, teeth passed through the 85 head and bent transversely forward, and a handle-socket having bifurcated prongs adapted to embrace the head and ribs to take into the corrugations, substantially as described. 90

3. The combination in a rake of the U-shaped head, having parallel top and bottom sides, provided with series of perforations to receive the teeth, and a corrugated side, the rear face of the central depression to engage 95 and hold the teeth in position, and a handle-socket, substantially as described.

In testimony whereof I have hereunto set my hand this 13th day of November, A. D. 1894.

FREDERICK E. KOHLER.
